UNITED STATES PATENT OFFICE

2,595,970

METHOD OF MAKING LUMINOUS SIGNS

Dennis M. McGill, Lancaster, Pa., assignor of
twenty-five per cent to Hugh Christi, Cocoli,
C. Z.

Application December 13, 1949, Serial No. 132,713

3 Claims. (Cl. 18—56)

1

This invention relates to the class of signs and more particularly to an advertising sign or the like which makes use of the inherent luminosity in the selected material from which the letters of the sign are made.

An object of this invention is to produce a novel sign formed from relatively strong and rigid symbols secured together by a novel method and in such a manner as to make full use of the inherent luminosity of the material from which the symbols are made.

A material which is preferably used in the manufacture of the signs is known to the trade under the name "Plexiglas." This material is of the acrylic resin group of plastics and is thermoplastic and will soften at temperatures of 220° to 320° F. It will not become liquid but when heated may be easily twisted, bent, shaped or stretched. Successive heatings do not weaken this material.

This material has the additional property, important for the purpose of this invention, in the fact that it bends light rays so as to emit them along its edges and from fractures upon its surfaces. Thusly, this material shows a luminous edge when the pieces are of substantial size. However, when these pieces are below a certain width with respect to the thickness, it will lose its luminous quality. Thus, it is very critical that a sign using this material be made from blanks of suitable size.

If the signs to be made from this material are not made of sufficiently large sized pieces, the luminous quality will be severely reduced. Thus, it is an additional object of the invention to produce means having a high degree of luminosity in which the strength of the sign is not materially reduced and in which full use is made of the blanks from which the symbols of the sign are made. By making use of a curved back for the symbols, such are composed of enough material to give the full luminous effect without adding unnecessary depth which will weaken the sign.

Yet another object of the invention is to produce a sign which will have two luminous edges for each symbol or letter.

Still further objects of the invention are to produce a sign which is strong, durable, highly efficient in operation, simple in construction and manufacture, relatively inexpensive and adapted to bring more material used into view, and which is quite pleasing in appearance.

These, together with the various ancillary objects of the invention which will become ap-

2

parent as the following description proceeds, are attained by this method of making luminous signs, a preferred manner being best understood with reference to the accompanying drawings wherein it is shown by way of example only the means used to make the luminous signs, wherein:

Figure 1 is a perspective view of the die preferably used to form a symbol from a suitable blank;

Figure 2 is a plan view of a blank used in forming a symbol;

Figure 3 is an elevational view of a finished symbol made by the method contemplated by the present invention; and

Figure 4 is a sectional view as taken along line 4—4 of Figure 3.

With continuing reference to the accompanying reference drawings wherein like reference numerals designate similar parts throughout the various views, reference numeral 10 generally designates a blank which is stamped from a sheet of the material to be used. The blank 10 is of such size and shape so that when it is placed between male and female dies 12 and 14 respectively a finished symbol generally indicated by reference numeral 16 will be formed which will make full use of the material of the blank.

Referring now to the male die 12, it will be seen that such is formed with a symbol 18 formed thereon which has its side walls 20 formed with approximately a 15° bevel rearwardly. Furthermore, as at 22 the forward edges of the symbol 18 are rounded for a purpose that will be readily understood after consideration of the further description below.

The male die 14 is formed with a recess 24 therein adapted to mate with the projecting symbol 18 of the die 12.

The blank 10 is heated to a temperature of about 300° F. and then placed between dies 12 and 14. The blank 10 may be heated by passing through a steam heated chamber or any other suitable zone of heat. After the blank has been placed between the dies 12 and 14, the dies are pressed together to form the symbol 16. The symbol is allowed to cool and then removed after which the edges 26 thereof are sanded to bring forth the inherent luminosity of the "Plexiglas" to provide a flat even surface for mounting and to bring forth the true shape of the symbol by removing uneven edges.

With reference to Figure 4 it will be seen that the letter is formed with two divergent out-

wardly extending portions 28 and 30 due to the 15° bevel in the side walls 20 of the male portion of the die. A central connecting portion 32 having a radius of curvature of at least three times the thickness of the material connects the outwardly extending portions 28 and 30 and together these members form an extremely strong symbol. In order to form completed signs out of the symbol 16 when finished, these symbols may merely be secured to a backing plate by cementing the rear surface of the central connecting portion 32 to said backing plate. Any other convenient means for securing the symbol 16 to the backing plate may be used, however, it is preferable to secure the symbols by a means remote from the edges 26 so that no shadow or member may cover the edges to mar their luminous and pleasing appearance.

A clear plastic face plate may be used and the symbols may be mounted on the rear side thereof with their point of attachment the luminous edges of the symbols themselves. The symbols are then viewed through the sheet. A clear plastic cement such as ethylene dichloride securely attaches the symbols to the face plate and does not interfere with the viewing of the luminous edges whatsoever.

Since from the foregoing, the advantageous results of this method of producing luminous signs is readily apparent, further description is believed to be unnecessary.

However, since numerous modifications will readily occur to those skilled in the art after a consideration of the foregoing specification and accompanying drawings, it is not intended to limit the invention to the precise method used and described but all suitable modifications thereof may be resorted to which fall within the scope of the appended claims.

Having described the invention, what is claimed as new is:

1. A method of producing a self-illuminable sign comprising the steps of stamping blanks from a flat sheet of resinous plastic material, passing said blanks through a zone of heat, placing said blanks between male and female dies, pressing said dies together to transform the flat blanks into symbols of trough-shaped form allowing said symbols to cool, removing said symbols and then sanding the inner and outer edges thereof to effect edge-lighting of said symbols and securing said symbols in spaced relationship to each other to spell out the desired sign by means attaching said symbols to a backing member at a point remote from said edges.

2. The method of making up a self-illuminable luminescent sign component susceptible of reflecting and glowing from a suitable source of light; the method steps consisting of first molding and transforming a flat sheet of moldable transparent light-reflecting acrylic plastic of prerequisite glossiness, size and thickness into a symbol of given shape and design whose molded portions are smooth, glossy and channel-shaped in cross-section, and second, abrading the respective inner and outer endless light-emitting marginal edges of the then existing flanges of said symbol to thus dull and render the same luminescent and to effect edge-lighting, the overall channel-shaped portion of said symbol providing the desired strength for light-reflecting properties and contrast between itself and said edges.

3. The method of producing a sign letter or an equivalent symbol which consists in following these steps; namely, first stamping a letter from a flat sheet of transparent acrylic plastics possessed of moldable properties and of a given minimum size and minimum thickness and whose marginal edges are substantially flat, second, heating said letter to a degree of moldable plasticity, third, pressing the same in a mold and transforming it from its original flat form to a form which is channel-shaped in cross-section and thus providing two spaced parallel flanges connected by a bight portion with said flanges in divergent relation, and fourth, abrading the marginal edges of said flanges, whereby to thus provide a letter which presents forwardly viewable spaced parallel edges in the same plane and wherein said edges, acting in conjunction with the letter proper not only delineate the outline desired, but are edge-lighted.
